Technical drawing of a mechanical assembly, likely a valve or pump component, with various numbered parts labeled 290 through 378. The drawing is a cross-sectional view showing internal components like a piston, rod, and valves. External parts include a handle and a base plate. The drawing is signed 'INVENTOR' and 'Benjamin F. Mayo'.

UNITED STATES PATENT OFFICE.

BENJAMIN F. MAYO, OF SALEM, MASSACHUSETTS, ASSIGNOR TO UNITED SHOE MACHINERY CORPORATION, OF PATERSON, NEW JERSEY, A CORPORATION OF NEW JERSEY.

HEELING MACHINE.

Application filed June 3, 1918, Serial No. 237,951. Renewed March 22, 1922. Serial No. 545,898.

To all whom it may concern:

Be it known that I, BENJAMIN F. MAYO, a citizen of the United States, residing at Salem, in the county of Essex, and State of Massachusetts, have invented certain Improvements in Heeling Machines, of which the following description, in connection with the accompanying drawings, is a specification, like reference characters on the drawings indicating like parts in the several figures.

My invention relates to machines for attaching heels to shoes and especially those in which the heels are nailed to the lasted 15 shoes. Such machines may be looked upon as belonging to one of two general types—those in which the nails are driven upwardly through the heel into the sole, in the manner disclosed in Patent No. 1,457,688, Glidden, 20 October 26, 1915, and those in which the shoe is inverted and the nails are driven downwardly, as illustrated in Patent No. 143,885, Pope, February 24, 1891. Shoe manufacturers frequently have a marked 25 preference for one of these forms of machine rather than the other. The requirements of manufacturers also vary with respect to the manner in which the machines are to be set in the shops relatively to the source of 30 power. Shoe shops are customarily long, rectangular buildings in which the power shafts run longitudinally at opposite sides adjacent to the walls. The work is brought 35 to and removed from the machines through aisles parallel to these walls and to the shafts. According to the type of machine employed and the practice of the manufacturers, it may be considered preferable in a 40 particular shop to set the machine back to the wall, so that each operator stands at the edge of the aisle with the helper between his machine and that next at the right and the rack at the left between the machines, or to 45 place the machines with the right side to the wall, the operator then being between the machines, the helper between the machine and the wall and the rack in the aisle. In the first instance, the operator has the 50 benefit of a good light upon the work, but it is somewhat inconvenient to introduce the rack into and remove it from the space between the machines. In the second arrangement, the distribution of light is less effective, while the racks may be moved directly 55 along the aisles to and from their places be-

side the machines. Since both methods of applying power may be utilized for either nail driving organization, there result four forms of machine which may be called for by shoe manufacturers. It is, of course, desirable that the maker of shoe machinery be able to meet the demands at the lowest cost of production and with the least investment for the maintenance of a stock of machines.

In view of such considerations, an object of this invention is to provide a machine universal in character, or in which a basic structure may be caused with relatively slight changes, involving the addition or subtraction of few parts, to take any one of the four forms, and to furnish such an organization performing its various functions in an effective manner.

In the attainment of this object, a feature 75 of the invention consists in so arranging the means for operating upon the work and their actuating means that they may be mounted at different relative normal points on their support. As to the operating elements, including a work-support and a nail-driving mechanism, these are variable in a novel manner in their relation to one another to permit the nails to be driven in opposite directions. This may be accomplished 80 by an interchangeable support and driving member, these being invertible upon their support to cooperate in one way or the other. With respect to the actuating means, these are adapted to be mounted in different angular positions upon the main support or frame with relation to the source of power. This allows the driving shafts or other actuating elements to be maintained in a constant relation to said source of power when 85 the frame and work-engaging elements are shifted.

Another feature of the invention concerns, regardless of the previously-mentioned normal arrangement of the operating elements, 100 the control of the work-engaging means to effect their sequential operation. Here plural members, as the work-support and nail-driving member, are independently connected to the actuating means furnishing the 105 power. One of these connecting means may be governed by the operator while the other acts automatically. The controlling means preferably consist of two clutches which exercise a reciprocal influence upon one an- 110

other in starting and stopping the movement of the work-engaging members.

In connection with the control by the operator of a work-engaging member which is also power-actuated, a feature of the invention relates to novel means for permitting these movements to be produced independently so that interference of the respective actuating means with the movement produced by the other is avoided. This means I have shown as an extensible member, as a rod connected at its extremities to the work-engaging member and the driving member, there being sections which move relatively when the operator exercises control and surfaces upon the sections which contact to transmit the power.

Other features of the invention are developed by the following description and the accompanying drawings, in which—

Fig. 1 illustrates in side elevation an embodiment of my invention in which the nails are driven downwardly into the work;

Fig. 2 is a front elevation of the machine, parts being removed and a portion of the distributing mechanism indicated in dotted lines;

Fig. 3 is a side elevation, looking in the opposite direction from Fig. 1, some of the elements being omitted and the driving shafts shown as extending from the front to the rear of the machine;

Fig. 4 is a horizontal section on the line 4—4 of Fig. 1;

Fig. 5 is an enlarged vertical section on the line 5—5 of Fig. 2;

Fig. 6 is a sectional detail on the line 6—6 of Fig. 5;

Figs. 7 and 8 are similar views on the lines 7—7 and 8—8, respectively, of Fig. 6;

Fig. 9 is an enlarged vertical section on the line 9—9 of Fig. 1;

Fig. 10 is an enlarged view in elevation, parts being broken away, of the heel and top lift presenting mechanism, together with the nail-loading mechanism, these being as employed in connection with an organization in which upward nailing is practised;

Fig. 11 is a broken top plan view of the mechanisms of Fig. 10;

Fig. 11^a is a view similar to Fig. 11 with the parts arranged for downward nailing and with the loading mechanism in its nail-delivering position;

Fig. 12 is an enlarged front elevation of the work-clamping mechanism;

Fig. 13 is a side elevation of said mechanism with parts in section;

Fig. 13^a is a horizontal section on the line 13^a—13^a of Fig. 13;

Fig. 14 is an elevation, corresponding to Fig. 1, of the machine as arranged for upward nailing;

Fig. 15 is a side elevation, corresponding to Fig. 3 as to the relation of the driving

shafts to the frame and to Fig. 14 with respect to the elements for operating upon the work:

Fig. 16 is a horizontal sectional detail on the line 16—16 of Fig. 15; and

Fig. 17 is an enlarged vertical section corresponding to Fig. 5 for the upward nailing arrangement of Fig. 14.

The frame of the machine consists of a rectangular base 20, from which rises a standard 22 having a lower forward extension 24 and an upper overhanging arm 26. Cleats 27 are fixed to the upper surface of the base in opposite pairs, and by engagement with grooves 29 in the foot of the standard and with the edges of said standard may position the latter in either of two positions at right angles to one another. The extension and arm are provided at their outer portions with lower and upper ways 31 and 28, respectively, to receive interchangeably the work-supporting elements and nail-driving elements, depending upon whether the direction of nailing be down or up. At the lower portion of the rear of the standard are three horizontally arranged pairs of recesses 30, 32 and 34 into which may be bolted bearings to carry actuating shafts extending either from the rear to the front of the machine or transversely thereof, depending upon the manner in which it is desired to apply power to the machine. The recesses 30 receive the main power shaft 36, while a secondary shaft 38 may be supported in either the recesses 32 or 34, according to whether the machine is to nail in a downward or upward direction. The frame is provided with various bosses, bearing surfaces and openings to facilitate the attachment and passage of the actuating elements in the different positions they will assume for the diverse arrangements of the machine.

I will first describe the organization in which the work-supporting and operating mechanisms are disposed for downward nailing under the influence of actuating shafts extending transversely of the frame. The recesses 30 receive the main power shaft 36, while a secondary shaft 38 may be supported in either the recesses 32 or 34, according to whether the machine is to nail in a downward or upward direction. The frame is provided with various bosses, bearing surfaces and openings to facilitate the attachment and passage of the actuating elements in the different positions they will assume for the diverse arrangements of the machine. I will first describe the organization in which the work-supporting and operating mechanisms are disposed for downward nailing under the influence of actuating shafts extending transversely of the frame.

Referring particularly to Figs. 1, 2 and 4, the main shaft 36 is journaled in bearings 42, 42 bolted in the recesses 30 at opposite sides of a central opening 44 between vertical halves of the standard 22, the outer extremity of the shaft being carried in a bearing in a bracket 46 secured at one of the short sides of the base. Upon the shaft 36 are pulleys 48 and 49, the first being idle and the second secured to the shaft to rotate therewith by a clutch mechanism which will later be described. The pulley 49 may be driven by a belt from any suitable source of power, and carries upon its hub a pinion 50 meshing with a gear 52 upon the shaft 38. The shafts 38 and 36 actuate the members co-operating with the work, these being, respectively, the jack 51 and the driver head 53.

53, the drivers 55 of which move into openings in a nail block 54 carried at the lower extremity of the arm 26. The jack is pivoted at 56 upon a slide 58 adjustably mounted 5 on a head 60, so that the jack may, in a general way, be correctly alined with the operating elements above it in a direction from the front to the rear of the machine. The normal separation between the work-engaging 10 surfaces of the jack and the nail block may be varied by adjusting the length of the jack post. This post is in sections 62, 64 (Fig. 14), the former fixed in a pivotal mounting on the head 60, the two sections 15 having right and left threads, with which cooperates a correspondingly threaded nut 66. This nut may be turned to lengthen or shorten the post, and in this movement the section 64 is guided by a reduced stem 68 20 operating within a bore in the opposite end of the section 62. The head 60 is guided in the ways 31 beneath gibs which are in sections 69 and 71 of different lengths, said head having pivoted to its under side at 70 a rod 25 72 articulated at its opposite extremity 74 to a bottom lever 76 fulcrumed at 78 on the lower portion of the extension 24 of the standard. At the rear portion of the lever 76 is a socket 80 to receive the spherical end 30 82 of a short lower back rod 84, the upper extremity of which is pivoted upon a crank pin 86 included in the secondary actuating shaft 38.

The drivers are carried by a plate 88 35 mounted on the head 53 guided in the ways 28, said plate being adjusted upon the head by the well-known wedge mechanism 90 to alter the extent of projection of the drivers into the openings of the nail block 54, and 40 thus the distance the nails are driven. To upwardly extending lugs 92 on the head 53 is pivoted a link 94, the upper extremity of which is in turn pivoted at 96 to a top lever 98 fulcrumed at 100 in the standard. A 45 socket 102 at the opposite end of the lever receives the ball tip 104 of the upper back rod 106. This rod moves between ways 108 at the rear of the frame, which, however, in the present instance exercise no guiding 50 function. At the bottom the rod 106 is articulated to a crank 109 of the shaft 36.

The gear 52 is joined to the shaft 38 by a 55 clutch 110 (Fig. 5), which may be of the Horton type, controlled by a treadle 112, while the pinion 50 on the shaft 36 is connected by a similar clutch 114 governed by 60 the companion clutch 110. The treadle 112 has plural fulcra, one at the rear at 116 and one near the center at 118. Pivoted on the 65 fulcrum 116 is a head 120 from which depends a stem 122 passing through an opening in a bracket 124 carried at the rear of the frame. Exerting its force to hold this fulcrum point normally downward is a helical spring 126 surrounding the stem 122 and

abutting against the under side of the bracket 124 and a collar 128 fixed upon the lower extremity of the stem. Extending upwardly from the fulcrum point 116 is a rod 130 passing through an opening at the rear 70 end of a bell-crank lever 132 fulcrumed on the frame. The portion of the rod 130 co-operating with the lever 132 is threaded and has upon it below the lever a nut 134 by which the time of action of the treadle upon 75 the lever may be varied. The opposite extremity of the lever 132 is provided with an overhanging portion co-operating with a projection 136 from an arm 138, this governing the clutch 110 and being fixed upon a 80 shaft 139 mounted to turn in the frame. The fulcrum 118 is furnished by a link 140 articulated upon one end of a lever 141 fulcrumed at 142 in the frame extension 24 and pivotally connected at its opposite end to 85 the head 60 carrying the jack. When the treadle 112 is depressed, the point 116 first acts as a fixed fulcrum, the tension of the spring 126 being sufficient at this time to resist upward movement of the head 120. 90 This draws down the link 140, swinging the lever 141 upon its fulcrum to raise the head 60 with the jack. The movement of the jack, while the bottom lever 76 remains stationary, is permitted by the formation of the upper 95 part of the rod 72, this being in sections 144 and 146 (Fig. 9). The upper section 144 has the pivotal connection 70, and at its opposite end is reduced in diameter, as indicated at 148, to enter a bore in the section 146. 100 The end 150 of the section 146 is frusto-conical to enter a corresponding recess in the section 144 about the reduced portion 148. These co-operating conical surfaces take lateral thrust which may be produced in the 105 rod 72 and tend to relieve strain upon the portion 148. After the heel seat of the shoe is brought, by the movement of the jack-actuating elements about the fulcrum 116, into contact with the heel which is to be secured 110 to it, movement of the pivotal connection 118 ceases and this becomes the fulcrum. Continued depression of the treadle now compresses the spring 126, raising the head 120 115 and the rod 130, the nut 134 contacting with 115 the lever 132 to remove the overhang from engagement with the projection 136 on the arm 138. This arm thereupon turns with the shaft 139 under the influence of a spring 120 152 connected to a yoke 154 which joins the arm 138 and an arm 156 fixed upon a shaft 157 rotatable in brackets 158 projecting from the rear of the frame. The movement of the arm 156 withdraws its end from contact with a projection 159 upon a carrier sleeve 160 of 125 the clutch 110, this sleeve controlling the position of rolls 162 between the wedge member 164 fast upon the shaft 38 and the ring 166 carried by the gear 52 (Fig. 6). This allows a spring 168 connecting the wedge 130

member and sleeve (Fig. 8) to turn said sleeve, so that the rolls are brought into engagement with the wedge member and ring to cause their rotation together until stopped by contact of the projection 159 with the arm 138, this arm, in removing the arm 156 from contact with the projection, having moved into proximity with the periphery of the sleeve. Both the arms 138 and 156 are in the form of casings (Fig. 5), each receiving a spindle 170 surrounded by a spring 172, which holds a head 174 upon the outer end of the spindle normally away from the adjacent face of the arm. When the projection 159 contacts with one of these heads it yields, compressing the spring and thus cushioning the shock produced by stopping the rotation of the sleeve.

As the clutch 110 thus brought into and out of engagement causes the rotation of the shaft 38 through a half-turn, the lever 76 is swung upon its fulcrum by the rod 84 to raise the rod 72 and the jack 51. In the first portion of this movement the section 146 of the rod is lifted under yieldable pressure to take up the space which has been produced by the preliminary movement of the jack under the influence of the first treadle depression, and thus brings the surfaces at 150 into contact. This corresponds to the measuring action commonly present in this class of machines. Thereafter the section 146 is positively raised to lift the jack and clamp the work firmly between it and the nail block for the nailing operation. To permit these take-up and pressure movements of the section 146, it is arranged as follows: This element 146 is itself in sections, the lower being furnished by a casing 176 (Fig. 9) into which the rod extends. The casing carries the pivotal connection 74 with the lever 76, and is guided in its vertical movement by projections 178 engaging the ways 31. In addition to its side wall, the casing includes a lower plug 180 and an upper head 182, both having threaded engagement with the casing. The rod section 146 extends through an opening in the head 182 and has pinned into a bore in its lower end the stem of a nut 184 of steep pitch. The nut co-operates with a screw 188 which has secured to its lower extremity a conical head 190 arranged to fit and frictionally engage a correspondingly tapered recess 192 in the plug 180. The screw is supported by a ring 194 surrounding its stem below the thread and pivoted on a central yoke-shaped portion of a lever 196 fulcrumed at 198 at the side of the ways 31. The lever 196 is adjustably limited as to its downward movement by a screw 200 threaded through an arm 202 bolted to the ways. By turning the screw 200 and swinging the lever upon its fulcrum, the normal spacing between the frictional engaging surfaces of the elements 190 and

192 may be altered. The pivotal connection between the lever 196 and the ring 194 is through opposite slots in the casing wall and two pairs of slots 203, 203 in the sides of the plug 180, one pair or the other permitting the passage of the pivots in connection with different arrangements of the actuating shafts. A spring 205, extending between the end of the lever opposite its fulcrum and the base, holds said lever in normal contact with the screw 200, while permitting it to rise in a portion of the movement of the rod 72. Ball bearings 204 are interposed between the head 190 and a plate 206 and the opposite sides of the ring 194, taking the thrust of the screw 188 in both directions. Surrounding the rod section 146 is a helical spring 208 resting upon the casing and having its upper end abutting against a collar 210 threaded upon the upper end of the rod section 146. During the first movement of the lever 76, while the space between the surfaces 150 is being taken up so that the sections 144 and 146 contact to move together, the casing 176 is raised, transmitting movement to the rod section 146 through the spring 208. At this time the screw 188 turns freely in the nut 184. This continues until the surfaces of the elements 190, 192 come into contact at a time determined by the adjustment of the screw 200. The co-operation of these surfaces frictionally locks the screw 188 to the casing, compelling the casing and rod section 146 to move as a single element. Thus locked together they act during the remainder of the oscillation of the lever 76 to raise the jack to clamp the work between it and the nail block. If the operator does not desire to employ the preliminary movement of the jack under the influence of the treadle, the sections 144 and 146 of the rod 72 may be secured to one another to move together by a pin inserted through aligned openings 213. As the clutch 110 is driving the shaft 38 to produce the work-clamping movement of the jack as just described, a cam projection 212 (Fig. 5), rotating with shaft 38, contacts with a lever 214 fixed upon a shaft 216 journaled in the frame parallel to the shaft 38. Fast upon the shaft 216 is an arm 218 similar in construction to the arms 138 and 156. The end of the arm 218 co-operates with a projection 220 from the sleeve 222 of the clutch 114. As described in connection with the clutch 110, of which 114 is a modified form, this allows its rolls, under the influence of springs 223 turning the carrier sleeve 222 (Fig. 7), to lock the ring 224 (Fig. 6) fixed to the pinion 50 to the inner wedge member 226 fast upon the shaft 36 to cause the latter to rotate. The crank 109 of the shaft 36 thereupon raises the back rod 106 to rock the top lever 98 for the performance of the nailing opera-

tion, which will later be described. As the sleeve 222 turns, a sliding member 228, operating in an inclined groove 230 in the member 226 and having a pin 231 entering a bore 233 in the sleeve and a rib 235 engaging an annular groove 237 in its interior, compels said sleeve to move to the left, as viewed in Fig. 6 of the drawings, by the travel of the member 228 in the groove 230 produced by the springs 223. This lateral movement brings the projection 220 into alinement with the end of an abutment 232, fixed to the frame and having a face extending adjacent to the end of the sleeve through nearly 180 degrees. After the crank has made a half-turn and the rod 106 is raised to its highest point, the projection 220 strikes the end 234 of the abutment, disengaging the clutch 114. The tension of the springs 223 thereupon moves the sleeve longitudinally under the influence of the sliding member 228 and inclined slot 230, so that the projection 220 is carried to one side of the end of the abutment 232 and moves in contact with its face, the inertia of the parts carrying them to the home position where the projection slips off the abutment at 236 and is stopped by contact with the end of the arm 218. By thus utilizing the momentum of the clutch to return it to its initial position, it is not necessary to employ as strong a braking effect to aid in overcoming its inertia. There is preferably applied to both actuating shafts, however, a constant frictional resistance furnished by opposite members 238, 238 (Fig. 1) drawn toward one another by screws 240 against the edges of discs 242 secured to the shafts. As the shaft 36 under its momentum makes the last half of its rotation, a cam 244 thereon strikes an arm 246 upon the shaft 139 and moves the arm 138, and through the yoke 154 the arm 156, back to the position illustrated in Fig. 5, so that the arm projection 136 is latched by contact with the overhanging portion of the lever 132. This, by the withdrawal of the arm 138 from the projection 159, releases the clutch 110, which makes a half turn and brings the shaft 38 and parts driven thereby back to normal. Springs 248 connecting the levers 214 and 246 with the frame exert their tension to draw the arm 138 against the latch lever 132 and toward the clutch 110 and the arms 156 and 218 respectively away from and toward the clutches. Their force may be adjusted by a bolt 250 which joins them to the frame.

Considering now the heel and top lift presenting mechanism and the nail transferring mechanism, this is illustrated in Fig. 1 and in greater detail in Figs. 10, 11 and 11^a. While Figs. 10 and 11 show these mechanisms as applied to the machine of Fig. 14, the direction of nailing in which is upward,

they will serve for consideration with the machine of Fig. 1, the chief difference between them being the relation of certain elements to the nail block, they in the first mentioned machine being above it and in 70 the second below. The heel and top lift holding devices of Fig. 11 would, therefore, be indicated by dotted lines for the organization of Fig. 1 where they come under the nail block and its support. The ways at 75 each side of the nail block would appear in full lines. These conditions are illustrated in Fig. 11^a. Bolted to the gibs of the ways 28 where they extend at 252 below the frame arm 26 (Fig. 3) and to the standard 22 of 80 the frame at 254 is an L-shaped casting 256 having separated vertical arms 258, 258, the upper ends of which abut against the lower surface of the extremity of the frame arm 26. At the outer portion of the apex 85 of this supporting member 256 are horizontal ways 260 (Fig. 2) to receive the nail block 54 provided with the usual nail receiving openings 262. Pivoted by a spindle 264 on the support to move across the nail block is a heel and top lift swing plate 266, on which are mounted the adjustable heel fork 268 with its breast gage 270 and the top lift fork and gage 272 and 274, respectively. Fixed to the spindle carrying the 90 swing plate and on the opposite side of the support is a lever having arms 276 and 278. A spring 280 joins the arm 276 to the support 256, drawing the swing plate about its pivot until it contacts with the yieldable 100 stop 282, such as is customarily provided in connection with such mechanisms and which is arranged to cushion the blow of the plate against it. The arm 278 has pivoted upon it a latch 284 with its engaging point arranged to normally contact in the movement of the swing plate with a projection 286 fixed to the adjacent face of the support 256. A spring 288 is seated in a vertical recess in a boss 290 depending from the 105 lever to hold the point of the latch in its raised position. To lower the point of the latch to release it from the projection 286, the tail 292 is struck by a projection 294 carried by the head 53 when it rises in its 110 nail driving movement.

On a bracket 296 bolted to the side of the support 256 is mounted a vertical spindle 298, about which turns a loader arm 300 carrying at its outer extremity a separable 120 loader block 302, in which are perforations 303 arranged in the form in which the nails are to be driven into the heel operated upon. Pivoted at 304 beneath the block is a loader gate 306 upon which rest the ends of the 125 nails delivered to the perforations 303. From a projection 308 upon the gate to the loader arm extends a helical spring 310, the force of which is exerted to turn the gate about its pivot 304 from beneath the loader 130

block. The gate is held normally in its position beneath the block by a latch 312 pivoted at 314 on the loader arm and drawn by a spring 316 between its tail 318 and the 5 arm into engagement with a pin 320 on the gate. The loader arm may be swung by its handle 322 to opposite extreme positions, determined by contact of adjusting screws 324 in short arms 326, 328 with opposite 10 faces of a stop arm 330 upon the bracket 296. When the arm 326 co-operates with the stop, the loader arm is in such a position that the openings 303 are aligned with the usual nail-tubes 332 supported upon a 15 holder 334 fixed to an arm 336 at the top of the spindle 298. To the tubes 332 nails are delivered from a suitable distributing mechanism, indicated at 338 in Fig. 2. This distributor is carried by a bracket 340 bolted 20 to the side of the frame and may be of the type described in Patent No. 1,325,752, Pope, December 23, 1919. The distributing mechanism is tripped, to cause it to deliver a charge of nails to the tubes 332, by 25 a rod 342 guided by an arm 344 secured to the spindle 298. To insure the loader occupying the desired position when it receives its load of nails, a latch 346 is pivoted at 348 on the arm 300 and is moved by 30 a compression spring 350, situated in a bore on the arm and contacting with the tail of the latch, so that its pointed end 352 enters a recess in the spindle. When the arm is 35 inclined face 354 of the engaging end of the latch permits it to be drawn out of the recess without great resistance, and the loader block passes over the nail block 54 until the openings 262 and 303 are aligned, 40 at which time the screw of the arm 328 is in contact with the stop arm 330.

The parts of the heel and top lift holding and the loading mechanisms being initially as illustrated in Fig. 11, with a heel and a 45 top lift held between the respective forks and breast gages and the block 302 supplied with a load of nails, upon swinging the loader arm toward the delivery position (Fig. 11^a), the side 355 of an angular end 50 portion 356 of an arm 358 (Figs. 1 and 11^a) secured beneath the loader arm strikes a roll 360 upon the arm 276. This turns the swing plate 266 and its supporting spindle 264 until the latching projections 284 and 55 286 engage to hold the plate with the heel 60 correctly positioned with respect to the surface of the nail block, ready to have the heel seat of a shoe upon the jack 51 pressed against it by the treadle-controlled mechanism previously described. As the openings 65 303 in the loader block come into alinement with those in the nail block 54, a curved face 362 of the portion 318 of the loader gate latch strikes a surface 264 on the rear 70 of the right hand way 28, withdrawing the

latch from engagement with the pin 320. This releases the loader gate, allowing the spring 310 to carry it from beneath the openings 303, delivering the nails to the openings in the nail block 54. The loader 75 arm is now swung back to its normal position, and in its travel a face 366 of the arm 308 of the loader gate, which arm is now in a position substantially at right angles to the latched relation shown in Fig. 11, or as 80 it appears in Fig. 11^a, comes into contact with a roll 368 mounted upon the rear of the upper face of the support 256. This resets the gate by moving it until the pin 320 is again engaged by the latch 312. A 85 cam member 370 fixed to the upper side of the loader arm contacts with the rod 342 and trips the mechanism of the nail distributor 338. This takes an appreciable time to operate, so that not until the arm 90 326 has reached the stop 330 is the load of nails delivered from the tubes 332 to the loader block. When under the influence of the actuating mechanism following the full depression of the treadle, the driver head 95 moves to project the drivers into the openings in the nail block and drive the nails, the projection 294 on said head contacts with the tail 292 of the swing plate latch. The latch is thereby swung out of contact 100 with the projection 286 upon the support, permitting the spring 280 to shift the swing plate to the position illustrated in Fig. 11, in which a top lift held between its fork 105 272 and breast gage 274 is brought over the heel of the jacked shoe, from which the driven nails have been left projecting. The portion 372 of the swing plate is now interposed between the drivers and the top lift to serve as a spanker plate, and upon a second actuation of the treadle and consequent movement of the jack the top lift is pressed thereby upon the protruding nails to secure it.

Were the loader arm to be moved more 110 than once from its nail receiving to its nail delivering position between operations upon the work by the mechanisms controlled by the treadle, the first load would be properly introduced into the openings 262 of the nail 115 block, while the succeeding loads would fall upon the swing plate and support and possibly interfere with the action of the machine. Means is provided for positively preventing this plural delivery, consisting of a stop arm 120 374 mounted to turn upon the spindle 264 and drawn against a pin 376 upon the arm 276 by a spring 378 joining the stop arm with a point upon the support. This arm 125 374 has a contact portion 380, which, in the first movement of the loader mechanism in which the swing plate is shifted to bring the heel holder to the nail block, is so situated that it does not interfere with such movement, the portion 382 of the arm 358 con- 130

tacting with the edge of the stop arm to turn it about the spindle 264 against the tension of the spring 378. After the swing plate has been turned on its pivot and latched by 5 the elements 284 and 286, the portion 380 lies upon the arm through which moves the portion 382. It therefore catches and holds the arm 300, the contact of the face 355 of the extension with the end of the arm 374 10 preventing the rotation of the latter about the spindle.

Difficulty may also be experienced in the use of a nail-loading mechanism as a result of making an incomplete movement of the 15 loader arm from its receiving to its delivering position. Since the load of nails in the block 302 would not be discharged as a result of the contact of the gate latch 312 with the portion 364 of the frame, the return of 20 the loader mechanism to its initial position would cause the distributing mechanism to drop a second load of nails upon the already filled openings of the loader block, unless there is means for preventing this. Such 25 means is here provided in the actuating member 370 carried by the loader arm to raise the rod 342 for tripping the distributing mechanism. This actuating member is in the form of a cam block, shown as curved 30 along the arc through which it travels into co-operation with the rod. As the arm swings to the left in Figs. 11^a and 11 in the delivering movement of the loader mechanism, a pivoted contact portion 381 at the 35 lower extremity of the rod (Fig. 10) yields so that said rod is not lifted and the distributing mechanism is not affected. When the arm 370 has passed the rod, the portion 381 straightens and upon the return of the 40 loader arm acts as a rigid continuation of the rod. As the inclined end 384 of the cam travels beneath the rod during the return, the latter is raised and is held as long as the 45 extended arcuate portion of the cam is beneath it, thereby tripping the distributor mechanism to cause it to discharge the succeeding load of nails to the loader block when its openings are alined with tubes 332. The relation of the cam to the loader arm is 50 such that it does not clear the end of the rod 342 in its movement to the left until the loader mechanism has reached its delivery position, in which the loader gate has been released and the load of nails supplied to 55 the nail block. Consequently for any incomplete movement, in which the nails are retained by the loader mechanism, the portion 381 does not straighten, the rod is not raised and the distributing mechanism cannot 60 doubly load the block 302.

To correctly position the work with respect to the nail block, there is a clamping device 388 to receive the rear portion of the shoe operated upon. It is mounted on a 65 slide 390 movable in ways 392 at the front

of the standard 22 of the frame between the extension 24 and the arm 26. The general organization is as illustrated in Fig. 1, and the details appear in Figs. 12 to 13^a. The position of the device in these figures last 70 mentioned is as arranged for upward nailing, but the parts and their relation to one another, save with respect to the inversion of the device as a whole, are identical with those in the machine nailing downwardly. 75 The slide is connected to the jack post by a sprocket chain 391 extending between a plate 394 secured to the end of the slide and the usual adjusting device 396 at the jack post, which enables the operator to vary the vertical relation of the clamping device to the post. The chain passes over a sprocket 398 mounted to rotate upon the jack slide 58. The clamping device is balanced by a weight 400 (Fig. 1) joined by a chain 402 to lugs 80 404 projecting from the rear of the slide 390 near its center. The chain is supported upon a sprocket 406 rotatable at the rear of the ways 392. Extending across the slide 390 are horizontal ways 408 in which is 85 mounted a secondary slide 410, from the front of which project arms 412 curved outwardly and upwardly, and each having a horizontal extension 414. At the forward extremity of each of the arm portions 414 is a 90 sleeve 416 situated horizontally, the axes of the sleeves being in alinement. These sleeves are arranged to turn in the arms and are internally oppositely threaded to receive screws 418, at the inner end of each of which 100 is a vertical carrier arm 420 provided with an inwardly inclined end portion 422. Near the junctions of the portions 420 and 422 is a horizontal way, into which projects a 105 flange 424 upon the work-engaging band 426 of the clamp, this band being of resilient sheet metal. The sides of the band are supported and guided by rolls 428 journaled in the ends 422 of the carrier arms. The band is movable horizontally to bring it 110 into proper transverse relation to the work by a screw 430 mounted to turn in a lug 432 on the slide 390, and being threaded into one of the arms 412.

The band is held normally outward in 115 the ways with its ends separated to the maximum extent to receive the work. For this purpose an arm 434, riveted at the center of the rear of the band and extending downwardly and rearwardly, has pivoted to it a 120 lever 436 fulcrumed at 438 upon a bracket 440. This bracket is mounted to move in ways in a vertical extension 442 of the slide 410, and is adjustably held therein by a screw 125 444 turning in the plate 394 and threaded into the bracket. The lever 436 is of the bell-crank type having an arm provided at its outer end with a horizontal cross extension 446. Adjacent to the ends of the extension the bracket 440 has arms 448 with 130

bore containing plungers 450 backed by springs 452. These springs force the plungers against the extension 446 of the lever, swinging it about its fulcrum to hold the band at its extreme forward position in the ways of the carrier arm portions 422. The extent to which the work may be moved back in engagement with the clamp is determined by a screw 454 threaded through the lever 436 and contacting with a portion of the slide 410. By adjustment of the screw 454, the point at which the work stops when the jack is swung in may be fixed and its relation to the nail block from the front to the rear of the machine correctly determined. By turning the screw 444, the bracket 440 may be raised and lowered, and this through the lever 436 and arm 434 swings the band about pivots furnished by the sleeves 416. This enables the operator to vary the angle of the band from the horizontal so that it may better co-operate with shoes the heels of which have wedge lifts, and therefore the heel seat and tread ends are not parallel.

The normal separation between the outer ends of the band may be altered by relative movement of the carriers 420, 422. To effect this, each of the sleeves 416 has at its inner end a pinion 456 connected by an idler 458 fixed on a short spindle journaled in the portion 414 of the clamp arm with a pinion 460 secured to a shaft 462. The shaft 462 is rotatably mounted at the inner ends of both the arm portions 414 and carries a hand wheel 464 by which it may be adjusted. By turning this hand wheel, the sleeves 416 may be rotated by the gearing in either direction. They thus act as nuts to shift the screws 418 longitudinally in opposite directions and with them the carrier arms and the ends of the band supported thereby.

When the jack is in its outer or work-receiving position, as it appears in Fig. 1 of the drawings, the clamping device is held lowered by the chain 391. When the jack post is swung in, the weight 400 raises the clamping device, so that, as the heel seat of the jacked shoe arrives beneath the nail block, the band 426 is positioned to receive it. The correct normal relation having been determined by adjustment of the screw 444 and the shaft 462, the band is moved along its ways by the engagement of the shoe until the screw 454 is in contact with the slide, at which time the band arms have been forced by the rolls 428 against the counter portion of the shoe to clamp it and the work is properly aligned for the nailing operation. After this has been completed, the swinging out of the jack post causes the chain 391 to lower the clamping device, and, as the shoe leaves the clamp, the band is carried to its normal opened or work-re-

ceiving position by the pressure of the springs 452.

Considering the general operation of this type of machine, the operator's helper supplies the holders 268, 270 and 272, 274 with a heel and a top lift, respectively, and swings the loader arm, the block of which has already received its load of nails, to the delivery position. As it travels, the loader arm sets the swing plate by contact of the end of the arm 358 with the roll 360, so that the heel is carried below the nail block. This movement of the swing plate so shifts the stop member 374 that a second delivery of nails cannot be effected until the nailing mechanism has operated. As the loader arm returns to its normal position where it is held by the latch 352, it trips the distributor mechanism by raising the rod 342, so that the loader plate is supplied with a fresh load of nails, a double load being rendered impossible by the length and position of the cam block 370 which actuates the rod 342. The operator may now jack the shoe to be heeled and swing it into engagement with the band clamp. Having accomplished this, he partially depresses the treadle 112, which, turning about its fulcrum 116, rises the jack until the heel seat of the shoe is in contact with the heel held under the nail block. Having ascertained that the relation of the shoe and heel is correct, the operator fully depresses the treadle and releases it, or it may be held down through two cycles of automatic operation. Its movement about the fulcrum 118 first trips the clutch 110 and the shaft 38 turns through half a rotation to take up the separation of the rod sections 144 and 146, and then, with the nut 184 and screw 188 of the rod clamped together by the conical friction surfaces at 190, 192, continues its movement to clamp the shoe and heel together between the jack and die block.

As the clutch 110 completes its half-turn, it trips the companion clutch 114 which, in its first half-rotation, turns the shaft 36 to lower the nailing head and drive the nails held by the nail block through the heel into the shoe. The last half of the rotation of the clutch 114 is accomplished idly under its own momentum to return it to its home position, and in doing this it trips the clutch 110 to cause this to be returned to normal. By this last half-rotation of the shaft 38, the jack with the shoe is lowered. When the nails are driven, the projection 294 upon the head 53 releases the latching projections 284 and 286, so that the spring 280 may shift the swing plate to bring the top lift held between the members 272 and 274 over the attached heel. A second full depression and release of the treadle causes the machine to perform another cycle of operations, in this case the work contacting with the

swing plate at 372 to spank the top lift upon the projecting nails. The jack being lowered at the end of this cycle, it is swung out and the heeled shoe removed, when the machine is ready for a succeeding operation.

If it is desired to so organize my improved machine that the work-support and nailing mechanisms are reversed in position, the latter operating upwardly as is illustrated in Fig. 14, it may readily be changed from the type hereinbefore described in the following manner: The gib sections 69 and 71 of the ways 31 are in such lengths that they may be transferred to the ways 28 and 108, respectively. The former receives the head 60 of the jack inverted, and in the latter is mounted the casing 176 of the section 146 of the jack-actuating rod 72, the section 144 having a ball head 470 substituted for the pivotal connection 70. The link 94 at the opposite end of the top lever is replaced by a shorter link 472. The supporting casting 256 is inverted to rest upon the top of the frame extension 24, being bolted to long gibs 474 rising above it and to the standard 22 at 476. A long link 478 joins the bottom lever 76 to the nailing head 53, this lever now being fulcrumed at 480 instead of at 78 to give a shorter stroke for the nailing mechanism than was employed in connection with the jack. The bearings for the shaft 38 are transferred to the recesses 34 in the frame, the clutches 110 and 114 being arranged as shown in Fig. 17 with the pin of the sliding member 228 placed in an opening 481 (Fig. 7) in the carrier sleeve opposite the opening 233. Compression springs 482 are used instead of the tension springs 40 to give the proper movements to the arms 214 and 246. A rod 484 connects the crank 109 to the bottom lever, and a link 486 is articulated to the crank 86 and to the casing 176. For the preliminary movement of the jack under the influence of the treadle, the lever 141 is fulcrumed at 488, being joined to treadle by a long link 490 and to lugs 492 near the rear extremity of the top lever by a short link 494. To unite the fulcrum point 116 of the treadle to the lever 132, controlling the clutch of the shaft 38 now situated above the main shaft, the short link 130 is replaced by a link 496 of the requisite length. To counteract the weight of the jack and its associated parts, a tension spring 497 is connected between the top of the ways 28 and the head 60. The swing plate 266 is mounted upon the same face of the support 256 as before, but, since it is now inverted and it is desired to have the plate oscillate in the same direction to present, respectively, the heel and top lift of the shoe, another plate with the holders in a reversed position is substituted. A reversed construction of the parts

mounted on the opposite end of the spindle 264 for actuating the swing plate is also substituted, and the catch 286 is repositioned upon the casting 256. The loader arm is moved down upon the spindle 298 and an arm 498, situated in a plane lower than the arm 358 (Figs. 10 and 14) replaces the arm 358. With the elements in this relation, the loader gate latch 312 is released by contact of its face 499 with a pin 500 rising from the swing plate. In the travel of the loader arm from its receiving to its delivering position, it is necessary to carry it above the heel holder until the arm has cleared this and is over the nail block. For this purpose, the hub of the arm 300 has a downward arcuate projection 502 riding over a corresponding upward projection 504 upon the arm 296. The contact of these projections maintains the proper raised relation until the loader block passes the heel holder, at which time the projection 502 has moved beyond projection 504 and a roll 506 rotatably mounted between lugs beneath the loader arm travels down an incline of a cam member 508 fixed at the right and near the rear of the support 256. This brings the loader block gradually to its correct vertical relation to the nail block. When the opposite movement occurs the contact between the roll and incline raises the arm until the projection 502 is above its companion projection 504, so that during the remainder of the travel in this direction these projections support the loader mechanism to clear the heel holder. As to the clamping device, it is reversed, the sprocket 406 being mounted higher upon the frame, and a lighter counter-weight 510 being employed, since here its only function is to assist the operator in raising the clamp when the jack is swung out. Other changes necessary to convert the down-nailing machine to the upnailing machine are of a minor character. The general operation of the machines is identical.

Figs. 3, 15 and 16 illustrate the arrangement of the driving shafts from front to rear of the frame when the elements for operating upon the work are, respectively, in the down and up driving relations. Referring to Figs. 3 and 16, the standard 22 is attached to the base 20 in a position at right angles to that which it occupied in the form of the machine first described, the base being always fixed to the floor in the same relation, with its long axis parallel to the power-shaft. The bearings 42 are replaced by yokes 512 bolted into the same recesses 30 and 32 and bridging the central opening 44 of the frame. These yokes have at their centers bearings 514 for the shafts, there being bearings 516 for the forward ends bolted within the opening 44. Bosses 518 on the yokes with bores therein furnished mountings for the shafts carrying 125

the clutch-controlling arms. A bracket 520 giving a greater space between it and the standard is secured at the same edge of the base as that to which the bracket 46 was attached, and furnishes an outer bearing for the main shaft 36. The only other essential difference in this organization from that of Fig. 1 lies in the position of the cranks 86 and 109, which are now turned through angles of 90 degrees. In the arrangement of Fig. 3 this is permitted without other change by the universal connections 82 and 104 of the back rods. In the up-driving machine of Fig. 15, however, this angular shifting of the crank 86 also turns the plug 180 at the bottom of the casing 176 through 90 degrees, the threaded connection 522 (Fig. 9) between the parts of the casing allowing this. In this position the second set of slots 203, at right angles to those used in the organization of Fig. 1, receives the pivotal connections for the adjusting lever 196. Otherwise the changes to the machine of Fig. 15 involve only the raising of the yoke 512 for the shaft 38 from the recesses 32 to the recesses 34, with a corresponding elevation of the inner bearing 516 for this shaft.

The work-positioning means or band-clamp and the transfer means or loader mechanism herein disclosed are not claimed by me per se, they being, respectively, inventions of John M. Benjamin and Henry B. Greenough, made the subjects of Patents No. 1,400,716, December 20, 1921, and No. 1,377,337, May 10, 1921.

Having fully described my invention, what I claim as new and desire to secure by Letters Patent of the United States is:

1. In a heeling machine, means for operating upon the work, actuating means for the operating means, and a support for the operating and actuating means, said support being constructed and arranged to permit said means to be mounted at different points upon it.

2. In a heeling machine, means for operating upon the work, actuating means for the operating means, and a support on which the operating and actuating means are independently mounted, said support being constructed and arranged to permit both said means to be mounted in different normal positions.

3. In a heeling machine, means for operating upon the work, actuating means for the operating means, and a frame provided with means for securing the operating and actuating means thereto at different relative points.

4. In a nailing machine, a work-support, a nail-driving mechanism and intermediate devices co-operating with the work, the support and driving mechanism being variable

in position to opposite sides of the intermediate devices.

5. In a nailing machine, a work-support and a nail-driving mechanism interchangeably arranged, and independent means for maintaining the support and driving mechanism in their interchanged positions.

6. In a nailing machine, a work-support and a nail-driving mechanism interchangeably arranged, and means for presenting nails to the driving mechanism in either position.

7. In a nailing machine, a work-support and a nail-driving mechanism, the support and driving mechanism being variable in position to permit the nails to be driven in opposite directions, and means for oppositely presenting nails to the driving mechanism.

8. In a nailing machine, a work-support and a nail-driving mechanism, the support and driving mechanism being variable in position to permit the nails to be driven in opposite directions, and invertible work-positioning means co-operating with the support.

9. In a nailing machine, a work-support and a nail-driving mechanism, the support and driving mechanism being variable in position to permit the nails to be driven in opposite directions, means for oppositely presenting nails to the driving mechanism, and invertible work-positioning means co-operating with the support.

10. In a nailing machine, a work-support and a nail-driving mechanism interchangeably arranged, and nail-supplying means variable in position to correspond to the arrangement of the driving means.

11. In a nailing machine, a work-support and a nail-driving mechanism interchangeably arranged, and work-positioning means variable in position to correspond to the arrangement of the support.

12. In a nailing machine, a work-support and a nail-driving mechanism interchangeably arranged, and nail-supplying means and work-positioning means variable in position to correspond to the arrangement of the support and driving means.

13. In a heeling machine, a frame provided with two ways, and a support and an operating member each constructed and arranged to move in either of the ways.

14. In a heeling machine, a frame provided with opposite ways and intermediate ways, a work-support and an operating member each constructed and arranged to move in either of the opposite ways, and a work-positioning member arranged to be inverted in the intermediate ways.

15. In a heeling machine, relatively movable work-engaging members and actuating mechanism therefor including a lever hav-

ing a plurality of fulcra arranged to vary the length of the stroke.

16. In a heeling machine, relatively movable and interchangeable work-engaging members, and actuating mechanism therefor including a member having two pivotal points respectively utilized in the different positions of the engaging members.

17. In a heeling machine, a plurality of movable work-engaging members, an actuating member arranged to co-operate with said members and being adapted to impart a movement of the same extent to all, and connections between the actuating member and engaging members arranged to change the extent of movement in accordance with the particular engaging member actuated.

18. In a heeling machine, a plurality of movable work-engaging members, an actuating member arranged to co-operate with said members and being adapted to impart a movement of the same extent to all, and a pivoted connecting member between the actuating member and engaging members, there being different pivotal points for the member depending upon to which engaging member it is connected.

19. In a heeling machine, a frame, movable work-engaging members arranged to be attached to the frame at different points, and actuating means for the engaging members constructed and arranged to occupy different positions upon the frame in accordance with the position of said engaging members.

20. In a heeling machine, a frame, movable work-engaging members arranged to be changed in position on the frame, and actuating members for the work-engaging members, one of said actuating members occupying the same position upon the frame for all positions of the engaging members and another actuating member being constructed and arranged to occupy different positions in accordance with the position of the engaging member which it actuates.

21. In a heeling machine, movable work-engaging members, a plurality of actuating members for the work-engaging members, and means through which the work-engaging members may be either yieldably or positively connected to the actuating members, said means with its yieldable and positive connections being in the form of a unitary structure arranged to be transferred from co-operation with one to another of the actuating members.

22. In a heeling machine, movable work-engaging members, a plurality of actuating members for the work-engaging members, a sectional rod, and means for yieldably or positively connecting the rod sections, said rod being arranged to connect a work-engaging member with different actuating members.

23. The combination with a frame, of a top and a bottom lever fulcrumed therein, a work-support mounted to move in the frame under the influence of either of the levers, and a rod organized to impart either a yielding or positive movement to the work-support and being arranged for connection with either of the levers.

24. In a heeling machine, a work-support, a movable member upon which the support is mounted, a member movable by an operator, a plurality of actuating members for the support, and connections to the operator-moved member arranged to be joined either to the member carrying the support or to an actuating member.

25. In a heeling machine, a frame, a head arranged for movement in different portions of the frame, a work-support carried by the head, plural actuating members to which the head may be connected, an operator-controlled member, and connections to the operator-controlled member arranged to be joined to the head in one position of the head and to an actuating member in another position of the head.

26. In a heeling machine, a frame, a head arranged for movement in different portions of the frame, a work-support carried by the head, actuating members for the head in its different positions, a treadle, and connections between the treadle and head including a lever having different fulcrum points upon the frame.

27. In a machine for operating upon shoes, a frame, movable work-engaging members carried thereby, and power-driven actuating members for the work-engaging members, the frame and actuating members being constructed and arranged to allow said actuating members to be moved into different angular relations to the frame to vary the application of power.

28. In a machine for operating upon shoes, a frame, movable work-engaging members carried thereby, and power-driven actuating members for the engaging members, the frame and actuating members being organized to permit said actuating members to be maintained in a constant relation to the source of power when the relation of the frame to said source of power is changed.

29. In a heeling machine, a frame, work-engaging members movable thereon, and a driving shaft for the engaging members, said frame being arranged to receive the driving shaft transversely or from front to rear.

30. In a heeling machine, a frame, work-engaging members movable thereon, a driving shaft for an engaging member, and bearings for the shaft, the frame having spaced vertical portions between which the shaft may extend and being arranged to permit

the bearings to be secured upon each of the vertical portions.

31. In a heeling machine, a movable work-engaging member, an actuating member therefor, a driving member arranged to occupy different angular positions, and mechanism between the driving member and actuating member including a connection permitting alteration in the position of the driving member.

32. In a heeling machine, a movable work-engaging member, an actuating member therefor, a driving member arranged to occupy different angular positions, and a member pivoted upon the driving member and having a universal connection with the actuating member.

33. In a heeling machine, movable work-engaging means, an actuating lever therefor, a driving shaft which may be arranged transversely or from front to rear of the machine and having a crank, and a rod engaging the crank and being provided with a ball and socket connection with the lever.

34. In a heeling machine, a movable work-engaging member, an actuating member therefor, a driving member arranged to occupy different angular positions, and a member connected to the driving and actuating members and to a relatively fixed point, the connecting member being in sections turning relatively to one another to permit the change in the position of the driving member.

35. In a heeling machine, a movable work-engaging member, an actuating member therefor, a driving member arranged to occupy different angular positions, and a member connected to the driving and actuating members and to a relatively fixed point, the connecting member being in sections turning relatively to one another to permit the change in the position of the driving member, one of said sections having a plurality of openings, one or another of which permits the passage of the connection to the relatively fixed point.

36. In a heeling machine, a frame, a work-engaging member movable thereon, an actuating lever for the work-engaging member, a driving shaft having a crank and being variable in position upon the frame, a rod connecting the crank and lever and having sections, one of which turns upon another and one of said sections being provided with a plurality of sets of openings, and an adjustable lever fulcrumed upon the frame and having pivotal connection with a rod section through different sets of openings in different positions of the shaft.

37. In a convertible heeling machine, a frame provided with ways, work-engaging and actuating members movable in said ways, and sectional retaining members for the movable members co-operating jointly

with one of the ways, said sections being adapted in the conversion of the machine to co-operate with other different ways.

38. In a heeling machine, a plurality of movable work-engaging means, actuating means for the work-engaging means normally disconnected therefrom, independent means for connecting the actuating means and work-engaging means, and means arranged for intercontrol of the connecting means.

39. In a heeling machine, a plurality of movable work-engaging means, actuating means for the work-engaging means, and independent means for connecting the actuating means and work-engaging means, one of the connecting means being controlled by the operator, and automatic means for controlling another connecting means.

40. In a heeling machine, a plurality of movable work-engaging means, actuating means for the work-engaging means, independent means for connecting the actuating means and work-engaging means, one of the connecting means being controlled by the operator, automatic means for controlling another connecting means, and means under the influence of the operator-controlled connecting means for controlling said other connecting means.

41. In a heeling machine, a plurality of movable work-engaging means, actuating means for the work-engaging means, and independent means for connecting the actuating means and work-engaging means, one of said connecting means exercising control over another.

42. In a heeling machine, a plurality of movable work-engaging means, actuating means for the work-engaging means, and independent means for connecting the actuating means and work-engaging means, said connecting means exercising reciprocal control over one another.

43. In a heeling machine, a plurality of movable work-engaging means, actuating means for the work-engaging means, independent means for connecting the actuating means and work-engaging means, one of the connecting means being controlled by the operator, automatic means for controlling another connecting means, and means under the influence of the operator-controlled connecting means for controlling said other connecting means which in turn influences that first mentioned.

44. In a heeling machine, a plurality of movable work-engaging means, actuating means for the work-engaging means, independent means for connecting the actuating means and work-engaging means, operator-controlled means for rendering one of the connecting means effective, and means controlled by said connecting means for rendering another connecting means effective.

45. In a heeling machine, a plurality of movable work-engaging means, actuating means for the work-engaging means, independent means for connecting the actuating means and work-engaging means, operator-controlled means for rendering one of the connecting means effective, means controlled by said connecting means for rendering another connecting means effective, and automatic means for rendering the last-named connecting means ineffective. 5
46. In a heeling machine, a plurality of movable work-engaging means, actuating means for the work-engaging means, independent means for connecting the actuating means and work-engaging means, operator-controlled means for rendering one of the connecting means effective, means controlled by said connecting means for rendering another connecting means effective, and means controlled by the last-named connecting means for rendering that first named ineffective. 10
47. In a heeling machine, a plurality of movable work-engaging means, actuating means for the work-engaging means, independent means for connecting the actuating means and work-engaging means, operator-controlled means for rendering one of the connecting means effective, means controlled by said connecting means for rendering another connecting means effective, and automatic means for controlling the return of the last-named connecting means to normal. 15
48. In a heeling machine, a plurality of movable work-engaging means, actuating means for the work-engaging means, independent means for connecting the actuating means and work-engaging means, operator-controlled means for rendering one of the connecting means effective, means controlled by said connecting means for rendering another connecting means effective, and automatic means for controlling the return of the last-named connecting means to normal under its own momentum. 20
49. In a heeling machine, a plurality of movable work-engaging means, actuating means for the work-engaging means, independent means for connecting the actuating means and work-engaging means, operator-controlled means for rendering one of the connecting means effective, means controlled by said connecting means for rendering another connecting means effective, automatic means for controlling the return of the last-named connecting means to normal, and means controlled through such return to normal for controlling the return of the first-named connecting means to normal. 25
50. In a heeling machine, two movable work-engaging means, rotatable driving means for each, a clutch for connecting each work-engaging means to its driving means, operator-controlled means for causing the engagement of one clutch, and automatic means for causing engagement of one clutch, and automatic means for causing engagement of the other clutch. 30
51. In a heeling machine, two movable work-engaging means, driving means, a clutch for connecting each work-engaging means to the driving means independently of the clutch of the associated work-engaging means, operator-controlled means for causing the engagement of one clutch, automatic means for causing engagement of the other clutch, and automatic means for causing the disengagement of both clutches. 35
52. In a heeling machine, two movable work-engaging means, rotatable driving means for each, a clutch for connecting each work-engaging means to the driving means, operator-controlled means for causing the engagement of one clutch, and means rotatable with such clutch for causing the engagement of the other clutch. 40
53. In a heeling machine, two movable work-engaging means, rotatable driving means for each, a clutch for connecting each work-engaging means to the driving means, operator-controlled means for causing the engagement of one clutch, means rotatable with such clutch for causing the engagement of the other clutch, and a relatively stationary member with which an element of said other clutch contacts to disengage it. 45
54. In a heeling machine, two movable work-engaging means, driving means, a clutch for connecting each work-engaging means to the driving means, operator-controlled means for causing the engagement of one clutch, means rotatable with such clutch for causing the engagement of the other clutch, a relatively stationary member with which an element of said other clutch contacts for a portion of its rotation to disengage it to return to normal by virtue of its momentum, and means for stopping said clutch when it reaches its initial position. 50
55. In a heeling machine, two movable work-engaging means, driving means, a clutch for connecting each work-engaging means to the driving means, operator-controlled means for causing the engagement of one clutch, means rotatable with such clutch for causing the engagement of the other clutch, a relatively stationary member with which an element of said other clutch contacts to disengage it, and means rotatable with the last-named clutch for causing the disengagement of that first named. 55
56. In a nailing machine, a movable work-supporting member, a movable nail-driving member, a source of power, a clutch for connecting each member to the source of power, operator-controlled means for causing the engagement of the clutch connecting the supporting member, said means disengaging said clutch at the end of a partial rotation, a controlling member rotatable with the 60

clutch of the supporting member, and means with which said controlling member contacts to cause the engagement of the clutch for the driving member.

5 57. In a nailing machine, a movable work-supporting member, a movable nail-driving member, a source of power, a clutch for connecting each member to the source of power, operator-controlled means for causing the 10 engagement of the clutch connecting the supporting member, said means disengaging said clutch at the end of a partial rotation, a controlling member rotatable with the clutch of the supporting member, means with 15 which said controlling member contacts to cause the engagement of the clutch for the driving member, and an abutment, with which the clutch for the driving member contacts to disengage it at the end of a partial 20 rotation.

58. In a nailing machine, a movable work-supporting member, a movable nail-driving member, a source of power, a clutch for connecting each member to the source of power, operator-controlled means for causing the 25 engagement of the clutch connecting the supporting member, said means disengaging said clutch at the end of a partial rotation, a controlling member rotatable with the 30 clutch of the supporting member, means with which said controlling member contacts to cause the engagement of the clutch for the driving member, and an abutment, with which the clutch for the driving member contacts to disengage it at the end of a partial 35 rotation, said clutch thereafter returning to its initial position by virtue of its momentum.

59. In a nailing machine, a movable work-supporting member, a movable nail-driving member, a source of power, a clutch for connecting each member to the source of power, operator-controlled means for causing the 40 engagement of the clutch connecting the supporting member, said means disengaging said clutch at the end of a half rotation, a controlling member rotatable with the clutch of the supporting member, means with which 45 said controlling member contacts to cause the engagement of the clutch for the driving member, a controlling member rotatable with the clutch for the driving member, and means with which the controlling member of the driving member clutch contacts to 50 cause the re-engagement of the clutch for the supporting member.

60. In a nailing machine, a movable work-supporting member, a movable nail-driving member, a source of power, a clutch for connecting each member to the source of power, operator-controlled means for causing the 55 engagement of the clutch connecting the supporting member, said means disengaging said clutch at the end of a half rotation, a 60 controlling member rotatable with the clutch

of the supporting member, means with which said controlling member contacts to cause the engagement of the clutch for the driving member, a controlling member rotatable with the clutch for the driving member, and means with which the controlling member of the driving member clutch contacts to cause the re-engagement of the clutch for the supporting member, the last-named clutch being disengaged when it reaches its initial 75 position.

61. In a heeling machine, opposite movable work-engaging members, a driving shaft for each member, a clutch for connecting each work-engaging member to its driving shaft, each of said clutches being provided with a projection for controlling its engagement, opposite controlling members adjacent to one clutch and being connected to move together to alternately engage the 80 projection, a single controlling member for engagement with the projection of the other clutch, a treadle to move the connected controlling members, and a cam movable with the clutch controlled by the connected members for governing the single member. 85

62. In a heeling machine, opposite movable work-engaging members, a driving shaft for each member, a clutch for connecting each work-engaging member to its driving shaft, each of said clutches being provided with a projection for controlling its engagement, opposite controlling members adjacent to one clutch and being connected to move together to alternately engage the 90 projection, a single controlling member for engagement with the projection of the other clutch, a treadle to move the connected controlling members, a cam movable with the clutch controlled by the connected members for governing the clutch controlled by the single member, and a stationary abutment 95 for contact with the projection of the clutch controlled by the single member. 100

63. In a heeling machine, opposite movable work-engaging members, a driving shaft for each member, a clutch for connecting each work-engaging member to its driving shaft, each of said clutches being provided with a projection for controlling its engagement, opposite controlling members adjacent to one clutch and being connected to move together to alternately engage the 105 projection, a single controlling member for engagement with the projection of the other clutch, a treadle to move the connected controlling members, a cam movable with the clutch controlled by the connected members for governing the clutch controlled by the single member, and a stationary abutment for contact with the projection of the clutch controlled by the single member. 110

64. In a heeling machine, opposite mov- 115

- able work-engaging members, a driving shaft for each member, a clutch for connecting each work-engaging member to its driving shaft, each of said clutches being provided with a projection for controlling its engagement, opposite controlling members adjacent to one clutch and being connected to move together to alternately engage the projection, a single controlling member for engagement with the projection of the other clutch, a treadle to move the connected controlling members, a cam movable with the clutch controlled by the connected members for governing the single member, and a stationary abutment for contact with the projection of the clutch controlled by the single member, said abutment being separated from the normal position of the clutch projection by a portion of a revolution and including a surface for engagement with the projection and extending into proximity with its normal position.
65. In a heelng machine, opposite movable work-engaging members, a driving shaft for each member, a clutch for connecting each work-engaging member to its driving shaft, each of said clutches being provided with a projection for controlling its engagement, opposite controlling members adjacent to one clutch and being connected to move together to alternately engage the projection, a single controlling member for engagement with the projection of the other clutch, a treadle to move the connected controlling members, and cams rotatable with the clutches for exercising reciprocal control of said clutches.
66. In a heelng machine, opposite movable work-engaging members, a driving shaft for each member, a clutch for connecting each work-engaging member to its driving shaft, each of said clutches being provided with a projection for controlling its engagement, opposite controlling members adjacent to one clutch and being connected to move together to alternately engage the projection, a single controlling member for engagement with the projection of the other clutch, a treadle to move the connected controlling members, a cam movable with the clutch controlled by the connected members for governing the single member, and a cam rotatable with the clutch controlled by the single member for governing the connected members.
67. In a machine for operating upon shoes, a movable work-engaging member, a power-driven member, connections including a member connected to the engaging member and a power-driven member and being variable in length, and a member controlled by the operator for moving the work-engaging member, said movement being permitted by the variation in the length of the connection.
68. In a machine for operating upon shoes, a movable work-engaging member, a power-driven member, connections including an extensible member between the engaging member and power-driven member, and a member controlled by the operator for moving the work-engaging member, said movement being permitted by the extensible connection, there being contacting surfaces formed upon the extensible member through which the movement of the power-driven member is transmitted.
69. In a machine for operating upon shoes, a movable work-engaging member, a power-driven member, connections including an extensible member between the engaging member and power-driven member, and a member controlled by the operator for moving the work-engaging member, said movement being permitted by the extensible connection, there being contacting frusto-conical surfaces formed upon the extensible member through which the movement of the power-driven member is transmitted.
70. In a machine for operating upon shoes, a movable work-engaging member, a power-driven member, connections including an extensible member between the engaging member and power-driven member, and a member controlled by the operator for moving the work-engaging member, said movement being permitted by the extensible connection, there being contacting frusto-conical surfaces formed upon the extensible member through which the movement of the power-driven member is transmitted.
71. In a machine for operating upon shoes, a movable work-engaging member, a power-driven member, connections including a sectional member having connection at its extremities to the engaging member and power-driven member, and a member controlled by the operator for moving the work-engaging member, said movement being permitted by relative movement of the sections.
72. In a machine for operating upon shoes, a movable work-engaging member, a power-driven member, connections including a sectional rod between the engaging member and power-driven member, and a member controlled by the operator for moving the work-engaging member, said movement being permitted by relative movement of the rod sections, there being a shoulder on one of the sections contacting with the end of another section to transmit movement from the power-driven member.
73. In a machine for operating upon shoes, a movable work-engaging member, a power-driven member, connections including a sectional rod between the engaging member and power-driven member, and a member controlled by the operator for moving the work-engaging member, said movement being permitted by relative movement of the rod sections, there being a shoulder on one of the sections contacting with the end of another section to transmit movement from the power-driven member, such contacting surfaces furnishing means to resist lateral thrust upon the sections.
74. In a machine for operating upon shoes, a movable work-engaging member, a power-driven member, connections including an extensible member having alined sections connected at their outer extremities to the engaging member and power-driven member,

and a member controlled by the operator and being joined to the connections between the engaging member and power-driven member for moving the work-engaging member, said 5 movement being permitted by the extensible connection.

74. In a heelng machine, a work-support, a power-shaft, a telescopic rod including sections sliding upon each other and connected 10 to the work-support and power-shaft, a treadle, and connections between the treadle and work-support.

75. In a machine for operating upon shoes, a movable work-engaging member, a power-driven member, and connections between the 15 members, said connections including inde-

pendently movable aligned sections arranged to contact to transmit movement from the power-driven member to the work-engaging member and to separate to permit manual 20 movement of the work-engaging member by the operator.

76. In a heelng machine, a member movable to apply pressure to the work, a movable nail-driving member, actuating means 25 for the members, and automatic means arranged to complete the pressure-applying movement before the initiation of the movement of the driving member.

In testimony whereof I have signed my 30 name to this specification.

BENJAMIN F. MAYO.

Certificate of Correction.

It is hereby certified that in Letters Patent No. 1,447,261, granted March 6, 1923, upon the application of Benjamin F. Mayo, of Salem, Massachusetts, for an improvement in "Heeling Machines," errors appear in the printed specification requiring correction as follows: Page 7, line 6, for the word "arm" read *arc*; page 8, line 94, for the word "rises" read *raises*; page 9, line 63, for the word "of" read *to*; same page, line 130, for the word "furnished" read *furnish*; and that the said Letters Patent should be read with these corrections therein that the same may conform to the record of the case in the Patent Office.

Signed and sealed this 29th day of May, A. D., 1923.

[SEAL.]

KARL FENNING,
Acting Commissioner of Patents.
